United States Patent Office

Des. 179,469
Patented Jan. 1, 1957

179,469

TRICYCLE

Henry D. Bishop, Harper Woods, Mich., assignor to Evans
Products Company, Plymouth, Mich., a corporation of
Delaware

Application March 2, 1955, Serial No. 34,817

Term of patent 14 years

(Cl. D34—15)

Des. 179,469

PAGE 2

Fig. 1 is a perspective view of a tricycle, showing my new design;

Fig. 2 is a perspective view thereof, showing the opposite side; and

Fig. 3 is a rear perspective view thereof.

The dominant features of my new design are shown in solid lines in the drawings.

I claim:

The ornamental design for a tricycle, as shown and described.
